UNITED STATES PATENT OFFICE

AMOS W. SNOW, OF NORWICH, CONNECTICUT.

IMPROVEMENT IN LOCKS.

Specification forming part of Letters Patent No. 58,688, dated October 9, 1866.

To all whom it may concern:

Be it known that I, AMOS W. SNOW, of Norwich, in the county of New London and State of Connecticut, have invented a new and useful Improvement in Latch-Locks; and I do hereby declare that the following is a full, clear, and exact description thereof, which will enable those skilled in the art to make and use the same.

The present invention relates to a certain new and useful improvement in latch-locks, and consists in inserting in a common casing or box, with the bolt of the latch, a series of tumblers, which tumblers are so arranged as to prevent the latch-bolt from being drawn in by the turning of the handle, connected therewith in the ordinary manner, except (by means of a suitable key) the tumblers are first brought or adjusted with regard to each other so as to admit of the same.

In accompanying plate of drawings my improvements in latch-locks are illustrated, Figure 1 being a view of the interior of the lock casing or box, showing the latch-bolt and arrangement of tumblers with regard thereto; Fig. 2, a transverse vertical section taken in the plane of the line $x x$, Fig. 1; and Figs. 3 and 4, detail views of keys adapted to the latch-lock shown in the preceding figures.

A in the drawings represents the box or casing of the latch-lock, made of a square shape, with one its side plates, B, susceptible of being removed; C, the latch-bolt, arranged within the lock-casing and connected with an ordinary door-handle, as in latch-locks of the usual construction or arrangement, a spiral spring, D, throwing out the latch when drawn in by the door-handle; b b, a series of spring-tumblers, which may consist of any desired number within the scope of the lock, arranged one upon another and turning upon a common fulcrum pin or stud, c, of the lock-casing. These tumblers at one and the same end are made of a forked shape, the width of the space between their two parallel prongs, $d d^2$, being the same in each tumbler, but having their lower fork-prongs, d^2 , of different widths, these tumbler-prongs being toward the key-hole E of the lock, in which a key, F, made

of suitable shape to bring or lift the several spaces or slots between the fork-prongs of the tumblers in one and a common line with each other, as shown in Figs. 1 and 2, when, as is obvious, they will allow the latch-bolt to be drawn in, its arm f passing into the said space or slots, the tumblers b b preventing the latch-bolt from being drawn in when in any other position than that above explained, thereby rendering it impossible to open the door to which such lock is applied, except with the use of the proper-shaped key for the lock, the operation of which upon the tumblers has been explained.

To prevent the lock from being picked or its tumblers moved without the proper key, I form around the key-hole, upon the inside of the lock, between it and the tumblers, a guard-plate, t, over which the key turns, as shown in Fig. 2 of the drawings, this plate, as is obvious, preventing the tumblers from being tampered with or operated without a proper-shaped key is used.

In the use of this lock for holding or setting the tumbler-slots in a common line, a key, G, of the shape shown in Fig. 3, is employed, the application of which to the lock is obvious and is shown in Fig. 1, which key, when turned up and against the tumblers, retains them in proper position for operating the latch-bolt, but when in the position shown in red in Fig. 1 is entirely removed from the tumblers. This key G is intended for use upon the inside of the door to which the latch-lock is applied.

In lieu of the key G, a key similar to that shown in Fig. 4 may be used, its operation being the same as before described for key G.

What I claim as new, and desire to secure by Letters Patent, is—

The arrangement of the latch-bolt C, with its arm f, the spring-tumblers b b, as described, and guard-plate t, constructed and operating, in combination with a suitable handle and key, in the manner herein specified.

AMOS W. SNOW.
